AUTOMATIC GRIP FOR LIFESAVING DEVICES

Jack Frankel, Brooklyn, N.Y.

Application February 12, 1943, Serial No. 475,611

7 Claims. (Cl. 227—49)

This invention relates to new and useful improvements in a life-saving device.

More specifically, the invention proposes the construction of a novel type of clamp for use in a life saving device for persons working in elevated positions on scaffolds and the like and arranged in a manner to be engageable with a safety belt and an adjacent guy rope.

Still further it is proposed to characterize the clamp by a bracket having a fixed jaw engageable against one side of the guy rope and slidably supporting a movable jaw arranged in a manner to be engageable against the guy rope on the side opposed to the side engaged by the fixed jaw.

A further object of the invention proposes a novel means for supporting the movable jaw upon the bracket in a manner to be movable towards the fixed jaw for rigidly gripping the guy ropes.

It is still further proposed to provide a novel means for moving the slidably mounted jaw towards the fixed jaw and which is arranged in a manner to permit the clamping action to be quickly effected.

Still further the invention contemplates an automatic grip device which will automatically reclose the slidably mounted jaw onto the guy rope in the event of an emergency. With this arrangement it is impossible for a person using the device to experience a fall of any distance. If a fall should start it will be arrested immediately.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view illustrating a man standing upon a scaffold and using a life saving device constructed in accordance with this invention.

Fig. 2 is a perspective view of the assembled life saving device per se.

Fig. 3 is a perspective view of the bracket and associated parts per se.

Fig. 4 is an end elevational view of Fig. 3.

Fig. 5 is a plan view of Fig. 3.

Fig. 6 is a horizontal sectional view taken substantially on the line 6—6 of Fig. 3.

Fig. 7 is a horizontal sectional view taken substantially on the line 7—7 of Fig. 3.

Fig. 8 is a vertical sectional view taken on the line 8—8 of Fig. 5.

Fig. 9 is a vertical sectional view taken on the line 9—9 of Fig. 5.

Fig. 10 is a fragmentary enlarged vertical sectional view taken on the line 10—10 of Fig. 7.

Fig. 11 is a fragmentary sectional view taken on the line 11—11 of Fig. 7.

Fig. 12 is a developed view of the waist engaging belt, per se.

The life saving device, in accordance with this invention, includes a belt 10 for engagement about the waist of a person operating from a suspended scaffold 11. The belt 10 is of conventional construction and includes a buckle 12 on one end. The buckle 12 has a pivotal tongue 13 selectively engageable with one of a plurality of openings 14 formed in the other end of the belt. Attached to spaced positions along the length of the belt 10 there is provided a pair of leg engaging straps 15 which are arranged to engage the top of the wearer's legs immediately adjacent the crotch. The positioning of the belt 10 and straps 15 upon the waist of a person is clearly illustrated in Fig. 1 of the drawings.

A clamp 16 is adapted to be attached to the belt 10 and a guy rope 17 projected downwards adjacent the scaffold 11. The clamp 16 is characterized by a bracket 18 having a pair of forwardly extending eye portions 19. Each of the eye pieces is provided with a downwardly extending fastening means by which the bracket 18 is attached to the belt 10.

Each of the fastening means is characterized by a flexible cable 20 projected through and having its ends secured to a rigid tube member 21 which acts to encase its cables. Mounted upon each of the cables adjacent the lower end of the tube members 21 there is a clamp 22 having a spring closed jaw 23. These clamps 22 are engaged with complementary rings 24 securely mounted upon the belt 10 at points adjacent the straps 15.

At one end the bracket 18 is integrally formed with a rearwardly extending jaw portion 25. This jaw portion 25 is arranged to extend along a side portion of the guy rope 17. The other end of the bracket 18 slidably supports a complementary jaw member 26 arranged to extend along the other side of the side portion of the guy rope 17 which is engaged by the jaw member 25. The adjacent faces of the jaw members 25 and 26 are formed with vertically extending semi-circular cut-outs 27 arranged to engage about the guy rope 17. The surfaces of the cut-outs 27 are provided with a plurality of serrations 28

for roughening these surfaces to more securely grip the guy rope 17.

The jaw member 26 is substantially U-shaped in formation and has its arms extending around a rearwardly extending lug 29 formed on the bracket 18. Each of the arms of the jaw member 26 is provided with a reduced portion provided with a laterally extending slot 30. A bolt 31 extends through each of the slots 30 and threadedly engages into the bracket 18 forming the slideable support for the jaw member 26.

A means is provided for moving the slideable jaw member 26 into and out of operative position with relation to the fixed jaw 25. This means is characterized by a hollow screw 32 which threadedly engages through an opening formed in the lug 29 and a solid screw 40 which threadedly engages through a hollow screw 32. The outer end of the solid screw 40 is provided with a wheel 33 securely held in position by a pin 34. The wheel 33 provides a means by which the screw 40 may be turned. The inner end of the solid screw 40 has an enlarged head 41 which is rotatively connected to the jaw 26 at a position between the side arms thereof. This rotative connection is accomplished by the enlarged head 46 engaging into a complementary opening 35 formed in the jaw member 26.

A pin 36 is projected inwards from one face of the jaw member 26 and engages into a complementary circular groove formed on the said enlarged inner end 41 of the screw 40.

Means is provided by which the screws 32 and 40 may be locked in relatively adjusted positions. This means comprises a set screw 43 threadedly engaged through the hollow screw 32 and abutting against a reduced shank portion 44 formed upon the solid screw 40.

A driven gear transmission connection 45 connects with a hollow screw 32, and is provided with a double acting clutch 46 by which the hollow screw 32 may be driven in one direction or the other. More specifically, the driven gear transmission 45 includes a spring motor 47 which is mounted on the bottom of the casing 48 of a double clutch 46. The driven shaft 49 of the spring motor 47 is provided with a beveled gear 50 which simultaneously meshes with the beveled gears 51 and 52 or shaft 58 of the double clutch 46. A lever 53 controls the double clutch 46. This lever is pivotally mounted intermediately on the lugs 54. One end of the lever 53 projects from an opening 55 formed in the top of the casing 48. The other end of the lever 53 is of fork shape and controls the shift collar 56 of the double clutch.

A spring 57 normally urges the lever 53 into one position in which the clutch 46 is closed in one condition in which rotations from the beveled gear 50 will be transmitted to gear 51 to drive said shaft 58 of the clutch in one direction. The details of the clutch 46 will not be given in this specification as it forms no part of the invention and double clutches of this type are generally known. However, it is pointed out that the clutch 46 is of such design that when the lever 53 is pulled to the right, specific reference being had to Fig. 10, the clutch collar 56 will be moved and the double clutch will be drawn so that now the rotations from the beveled gear 50 are transmitted through the beveled gear 52, to drive the shaft 58 in the opposite direction. The shaft 58 is provided with a gear 59 which connects with a train of gears 60, 61. The gear 60 is merely an idler gear rotatively mounted on the stud 62.

The gear 61 is coaxially mounted on the outer end of the hollow screw 32.

Means is provided for limiting the unscrewing of the hollow screw 32. This means includes a stationary peg 63 which projects from the bracket 18 and which engages a groove 64 formed in the adjacent side of the gear 61. This groove 64 is concentric with the center of the gear 61 and extends through a distance of substantially 320°, as illustrated particularly in Fig. 11.

The operation of the device is as follows:

A person about to work upon a scaffold similar to that shown at 11 on the drawings, engages the belt 10 about his waist. The straps 15 are engaged about the top of the legs. The clamps 22 of the clamp 16 are then engaged with the rings 24 mounted on the belt 10. The guy rope 17 is then engaged between the jaw members 25 and 26 of the clamp 16. The set screw 43 is then loosened and the wheel 33 is turned to move the screw 40 inwards through the screw 32 and thus move the jaw member 26 towards the jaw portion 25 to firmly grip the guy ropes 17. With the life saving device thus assembled it will be noted that it is practically impossible to fall to the ground in the event that a person loses his footing on the scaffold, or if one of the ropes from the scaffold should break.

If it is desired to hoist or lower the scaffold and it becomes necessary for the clamp 16 to be moved upwards or downwards upon the guy rope 17, it is merely necessary to move the projecting end of the lever 53 so as to throw the clutch 46. The spring motor 47 now functions to drive the shaft 58 backwards and this rotation will be transmitted by the gears 59, 60 and 61 to the hollow screw 32. The hollow screw will turn substantially 320° or so, depending on the angular distance of the groove 64. Then the spring motor 47 is restrained and stops. However, when the screw 32 unscrews the amount mentioned the jaw member 26 is moved outwards, and now the clamp 16 will be loose on the guy ropes 17. Thus the clamp 16 may be shifted upwards or downwards.

In the event a person loses his footing, or the scaffold starts falling, at this instant he merely drops the lever 53. The spring 57 moves the lever 53 back into its original position, throwing the clutch 46 back to its original position. Then the spring motor 47 drives the shaft 58 in the opposite direction. This rotation will be transmitted by the gear 53, 60 and 61 to screw back the hollow screw 32 which moves the jaw member 26 back into its position, catching and gripping the guy rope 17. The fall is thus arrested.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a life saving device for persons working in an elevated position near a guy rope and provided with a safety belt, a clamp attached to said safety belt, and comprising a bracket having a pair of front eye portions for fastening means by which it may be connected with said safety belt, said bracket having a rearwardly extending jaw portion for extending along a side portion of said

guy rope, a jaw member complementary to said jaw portion for extending along the other side of said side portion of said guy rope, said jaw member being slidably mounted on the rear of said bracket, a lug projecting rearwards from said bracket and extending along the outer side of said jaw member, a hollow screw threadedly engaging through said lug, a screw threadedly engaging through said hollow screw and rotatively connected with said jaw member for setting said jaw member to grip said guy rope in association with said jaw portion, means for releasably locking said screws together, a driven gear transmission connecting with said hollow screw and having a double acting clutch by which said hollow screw may be driven in one direction or the other direction, and means for limiting unscrewing of said hollow screw, said means for releasably locking said screws together comprising a set screw mounted through the hollow screw and engaging the internal screw, said last-named screw having a reduced section against which the set screw clamps.

2. In a life saving device for persons working in an elevated position near a guy rope and provided with a safety belt, a clamp attached to said safety belt, and comprising a bracket having a pair of front eye portions for fastening means by which it may be connected with said safety belt, said bracket having a rearwardly extending jaw portion for extending along a side portion of said guy rope, a jaw member complementary to said jaw portion for extending along the other side of said side portion of said guy rope, said jaw member being slidably mounted on the rear of said bracket, a lug projecting rearwards from said bracket and extending along the outer side of said jaw member, a hollow screw threadedly engaging through said lug, a screw threadedly engaging through said hollow screw and rotatively connected with said jaw member for setting said jaw member to grip said guy rope in association with said jaw portion, means for releasably locking said screws together, a driven gear transmission connecting with said hollow screw and having a double acting clutch by which said hollow screw may be driven in one direction or the other direction, and means for limiting unscrewing of said hollow screw, said driven gear transmission including a spring motor.

3. In a life saving device for persons working in an elevated position near a guy rope and provided with a safety belt, a clamp attached to said safety belt, and comprising a bracket having a pair of front eye portions for fastening means by which it may be connected with said safety belt, said bracket having a rearwardly extending jaw portion for extending along a side portion of said guy rope, a jaw member complementary to said jaw portion for extending along the other side of said side portion of said guy rope, said jaw member being slidably mounted on the rear of said bracket, a lug projecting rearwards from said bracket and extending along the outer side of said jaw member, a hollow screw threadedly engaging through said lug, a screw threadedly engaging through said hollow screw and rotatively connected with said jaw member for setting said jaw member to grip said guy rope in association with said jaw portion, means for releasably locking said screws together, a driven gear transmission connecting with said hollow screw and having a double acting clutch by which said hollow screw may be driven in one direction or

the other direction, and means for limiting unscrewing of said hollow screw, and spring means for normally urging said double acting clutch in one direction in which the driven gear transmission screws the hollow screw inwards for closing the jaw member.

4. In a life saving device for persons working in an elevated position near a guy rope and provided with a safety belt, a clamp attached to said safety belt, and comprising a bracket having a pair of front eye portions for fastening means by which it may be connected with said safety belt, said bracket having a rearwardly extending jaw portion for extending along a side portion of said guy rope, a jaw member complementary to said jaw portion of said guy rope, said jaw member being slidably mounted on the rear of said bracket, a lug projecting rearwards from said bracket and extending along the outer side of said jaw member, a hollow screw threadedly engaging through said lug, a screw threadedly engaging through said hollow screw and rotatively connected with said jaw member for setting said jaw member to grip said guy rope in association with said jaw portion, means for releasably locking said screws together, a driven gear transmission connecting with said hollow screw and having a double acting clutch by which said hollow screw may be driven in one direction or the other direction, and means for limiting unscrewing of said hollow screw, and spring means for normally urging said double acting clutch in one direction in which the driven gear transmission screws the hollow screw inwards for closing the jaw member, and a lever for throwing said clutch.

5. In a life saving device for persons working in an elevated position near a guy rope and provided with a safety belt, a clamp attached to said safety belt, and comprising a bracket having a pair of front eye portions for fastening means by which it may be connected with said safety belt, said bracket having a rearwardly extending jaw portion for extending along a side portion of said guy rope, a jaw member complementary to said jaw portion for extending along the other side of said side portion of said guy rope, said jaw member being slidably mounted on the rear of said bracket, a lug projecting rearwards from said bracket and extending along the outer side of said jaw member, a hollow screw threadedly engaging through said lug, a screw threadedly engaging through said hollow screw and rotatively connected with said jaw member for setting said jaw member to grip said guy rope in association with said jaw portion, means for releasably locking said screws together, a driven gear transmission connecting with said hollow screw may be driven in one direction or the other direction, and means for limiting unscrewing of said hollow screw, and spring means for normally urging said double acting clutch in one direction in which the driven gear transmission screws the hollow screw inwards for closing the jaw member, and a lever for throwing said clutch, said lever being manually releasable whereupon said spring functions.

6. In a life saving device for persons working in an elevated position near a guy rope and provided with a safety belt, a clamp, comprising a bracket attached to said safety belt and having an integral rearwardly extending jaw portion for extending along a side portion of said guy rope, a jaw member slidably mounted on the rear face of said bracket to engage the other side of said side portion of said guy rope, a lug formed on said bracket along the outer side of said jaw member,

a hollow screw threadedly engaging through said lug, a screw threadedly engaging through said hollow screw and having its end engaging a recess in said slidable jaw member, a pin on said slidable jaw member engaging a circular groove in said screw for rotatively connecting said inner screw and said jaw member so that rotations of said screw will set said slidable jaw member to grip said guy rope with said jaw portion, a set screw threadedly engaged through said hollow screw and abutting the inner screw for locking the screws together as a unit, a driven gear transmission terminating in a gear mounted on said hollow screw and having a double acting clutch by which said hollow screw may be turned in one direction or the other, and a peg projecting from said bracket and engaging a groove in the adjacent face of said gear on said hollow screw limiting turning of said hollow screw to positions in which said slidable jaw member engages said guy rope or is free of said guy rope.

7. In a life saving device for persons working in an elevated position near a guy rope and provided with a safety belt, a clamp, comprising a bracket attached to said safety belt and having an integral rearwardly extending jaw portion for extending along a side portion of said guy rope, a jaw member slidably mounted on the rear face

of said bracket to engage the other side of said side portion of said guy rope, a lug formed on said bracket along the outer side of said jaw member, a hollow screw threadedly engaging through said lug, a screw threadedly engaging through said hollow screw and having its end engaging a recess in said slidable jaw member, a pin on said slidable jaw member engaging a circular groove in said screw for rotatively connecting said inner screw and jaw member so that rotations of said screw will set said slidable jaw member to grip said guy rope with said jaw portion, a set screw threadedly engaged through said hollow screw and abutting the inner screw for locking the screws together as a unit, a driven gear transmission terminating in a gear mounted on said hollow screw and having a double acting clutch by which said hollow screw may be turned in one direction or the other, and a peg projecting from said bracket and engaging a groove in the adjacent face of said gear on said hollow screw limiting turning of said hollow screw to positions in which said slidable jaw member engages said guy rope or is free of said guy rope, said groove in said gear being arranged in an arc concentric with the center of said gear and extends a distance of substantially 320 degrees.

JACK FRANKEL.
